[57] **CLAIM**

The ornamental design for a storage cube unit with drawer, as shown and described.

DESCRIPTION

FIG. 1 is a top, front and left side perspective view of a storage cube unit with drawer showing my new design, with the drawer partially opened; the opposite side being a mirror image thereof;

FIG. 2 is a front elevational view of the storage cubes with drawer shown in FIG. 1;

FIG. 3 is a rear elevational view thereof;

FIG. 4 is a side elevational view thereof;

FIG. 5 is a top plan view thereof;

FIG. 6 is a bottom plan view thereof; and,

FIG. 7 is a top, front and left side perspective view with the drawer closed; the opposite side being a mirror image thereof.
